Patented Nov. 14, 1922.

2 SHEETS—SHEET 2.

UNITED STATES PATENT OFFICE.

WALDO A. HOWLAND, OF ADAMS, MASSACHUSETTS.

ELECTRICALLY-ACTUATED MEANS FOR OPERATING VACUUM-BREAKER VALVES.

Application filed April 14, 1921. Serial No. 461,360.

To all whom it may concern:

Be it known that I, WALDO A. HOWLAND, a citizen of the United States, residing at Adams, in the county of Berkshire and State 5 of Massachusetts, have invented certain new and useful Improvements in Electrically-Actuated Means for Operating Vacuum-Breaker Valves, of which the following is a specification, reference being had to the accompanying drawings.

This invention relates generally to means for breaking the vacuum in steam plants, and particularly to certain improvements in the controller for operating the vacuum 15 valve illustrated in my application for patent filed April 10, 1920, Serial #372,818.

In the application above referred to, there is illustrated a vacuum valve which is operated by means of a piston, this piston in 20 turn being operated by the inlet of water to the piston chamber, the inlet of water being in turn controlled by a float operated water inlet controlling valve.

The present invention contemplates the 25 provision of means whereby steam or other motive fluid may be admitted to the piston chamber to cause the lifting of the vacuum valve and the consequent breaking of the vacuum in the exhaust pipe of the engine instead of using water for this purpose.

In the prior application above referred to, the controlling valve as illustrated is operated by means of a float which is shown as disposed within a float chamber connected 35 to the condenser of the engine so that when water commences to rise in the condenser the water will also rise in the float chamber, lifting the float and operating the controlling valve to cause the breaking of the 40 vacuum.

The general object of the present invention is to provide means whereby the controlling valve may be actuated by other means than said float, and particularly to 45 provide means whereby the controlling valve may be actuated to cause the breaking of the vacuum when an electrically actuated accident engine stop is operated to thus provide means whereby when an observer 50 touches an electrical push button in some part of the mill, to thereby actuate an accident engine stop and cause the steam to be shut off from the engine. At the same instant of time the controlling valve will be

actuated to cause the destruction of the 55 vacuum even before the machinery is still.

A further object is to provide means of this character wherein when the controlling valve is shifted through the actuation of the accident engine stop or through other electrically controlled means, the controlling valve will remain in this shifted position to thereby hold the vacuum valve in its open 60 position until the controlling valve is released by hand.

Still another object is to provide a mechanism of this character in which the controlling valve is primarily float operated but in which a solenoid or magnet is used to operatively engage the controlling valve to 70 shift it to a position to cause the opening of the vacuum valve, and in this connection to provide an improved electro-magnetic mechanism of a very simple and yet effective character mounted upon the float chamber itself which shall be very powerful, which shall be relatively compact, and in 75 which the magnetic mechanism will be fully protected so that only a minimum of care is necessary, a further object being to provide a mechanism of this character wherein no springs are used and which, therefore, is not liable to get out of order, which is 80 instantaneous in its action, and which may be readily connected up with the accident 85 stop or like mechanism.

Other objects will appear in the course of the following description.

My invention is illustrated in the accompanying drawings, wherein:—

Figure 1 is an elevation of a vacuum valve controlling mechanism constructed in accordance with my invention and applied to a condenser;

Figure 2 is a side elevation of the float chamber, the controlling valve, the vacuum valve and the motor therefor, the exhaust pipe being shown in section;

Figure 3 is a vertical sectional view of the float chamber, the controlling valve and the 100 electro-magnetic means for actuating the controlling valve;

Figure 4 is a top plan view of the construction illustrated in Figure 3;

Figure 5 is a fragmentary vertical sectional view of the controlling valve showing 105 the controlling valve raised to permit the passage of steam to the motor;

Figure 6 is an elevation partly in section of the motor and the vacuum valve and its seat;

Figure 7 is a section on the line 7—7 of Figure 3;

Figure 8 is a top plan view of the head 31;

Figure 9 is an elevation thereof;

Figure 10 is a fragmentary sectional view of the upper end of the magnetically actuating means for operating the valve, showing the position of said magnetically operated means when the magnet is energized, the valve lifted and the locking pin dropped.

15 Referring to these drawings, it will be seen that I have illustrated in general the mechanism which is fully described and illustrated in my prior application for patent above referred to, this mechanism including a cylinder 10 having heads 11 and 12 at its opposite ends, the head 12 being provided with an opening in its center which is connected with a condenser of an engine, as by means of a pipe 13. The head 11 also is connected with the upper portion of the condenser above the water line thereof by the pipe 14. The head 11 is also provided with a central aperture for the passage of a float rod.

30 Disposed within the cylinder 10 is a float 15 which is preferably an open bottom, metal float, though it may be of any suitable material. Attached to this float and extending upward therefrom is a stem 16. This stem extends up through the aperture in the center of the head 11.

40 Mounted upon suitable supports, as for instance the supporting bolts or posts 17, is a controlling valve casing 18. This valve body is hollow to form a longitudinally extending chamber, and connected to the upper end of this chamber is a steam pipe 19 which is connected to a source of steam or to a source of any other fluid pressure. Disposed within the chamber but spaced a distance from the upper end thereof is a bushing 20 which rests upon a shoulder 21 and is formed to provide a valve seat for a spherical valve 22. This bushing 20 is annular in 45 form and this central opening of the bushing is, of course, smaller than the spherical valve 22 so that when this valve 22 is lowered it rests upon the upper edge of the bushing and closes passage therethrough.

50 Disposed in the lower end of the chamber is a bushing 23 resting upon a shoulder 24 and below this bushing there is formed the exhaust chamber 25. Between the bushings 20 and 23 there is provided a chamber 26, this chamber communicating by a pipe 26^a with the motor which controls the vacuum valve, as will be later stated.

60 Extending through the lower end of the casing 18 is a stem 27 which is longitudinally shiftable through the valve casing.

This stem from its upper end downward a predetermined distance is hollow or tubular, as at 28, and the stem is formed at the lower end of this tubular portion with an exhaust port or ports 29. When this stem 70 is lowered, these exhaust ports discharge into the exhaust chamber 25, from which an exhaust pipe 30 leads, but when the stem is raised the exhaust port or ports 29 are carried up and closed by the sleeve 23 (see Figure 75 5). When the stem is raised so that the exhaust port is closed by the sleeve 23, the upper end of the stem engages the valve 22 and lifts it from its seat. It will be seen that the upper end of the stem has an exterior diameter smaller than the interior diameter of the bushing 20 so that when the stem is lowered and the valve 22 is on the seat, steam returning through the pipe 27 can pass into the chamber 26, then upward around the 80 stem into the space immediately beneath the valve 22, then downward through the tubular stem and out through the exhaust ports 29 into the exhaust chamber 25, and so out through the exhaust pipe 30. The stem 27 90 at its lower end carries a head 31, this head being split and held clamped upon the stem by means of a clamping screw 32 or in any other suitable manner. The stem 16 of the float 15 is disposed below this head 31 so 95 that when the float has risen a predetermined distance, the stem will strike the head 31 and lift this head, lifting the stem 27 and thereby lifting the valve 22.

100 The pipe 26^a is connected to a motor of the character fully illustrated in my prior application for patent. This motor as now illustrated comprises a cylinder 33 wherein is disposed a piston 34. The pipe 26^a opens through the bottom of this cylinder 25. The 105 upper end of the stem 34^a carries upon it a depending yoke 35 which extends below the cylinder 25 and is pivotally connected, as at 36, to a vacuum valve 37 resting upon a seat 38. Cylinder supports 39 extend upward 110 from this seat 38. Obviously when steam or other motive fluid enters through the pipe 26^a into the lower end of the cylinder, the piston 34 will rise, raising the valve 37 from its seat. The valve will remain raised so 115 long as the steam or other motive fluid fills the space below the piston, but when the controlling valve has been shifted so as to prevent the inlet of steam to the cylinder 33 and permit the outlet of steam therefrom, 120 the piston 34 will descend by gravity and this will lower the vacuum valve 37 onto its seat. A spring 40 may be disposed within the head of the cylinder 33 to bear against the piston and cause its return. I do not 125 wish to be limited to this, however. A plurality of ports 41 are provided in the upper end of the cylinder 33 to permit the discharge of any water which may have leaked past the piston. I do not wish to be limited 130

to the particular construction of the vacuum valve and its motor illustrated, as these details form no part of my present invention.

It will be obvious now from what has gone before that when the water in the condenser A rises above a certain amount, due to there being more intense vacuum in the cylinder than at the condenser, which condition may be caused by the stoppage of the air pump or the stoppage of the circulating pump before the engine has stopped or because the engine has no free exhaust to the air, then as soon as the rising water seals the inlet pipe 13 leading to the chamber 10, the vacuum existing higher up in the condenser at once begins to assist in causing the water to enter the chamber 10 below the float or piston 17 and will assist in the quick movement of the motor valve stem 16. Thus, for instance, if water begins to rise above its normal height in the condenser or in the exhaust pipe to the feed water heater and thus is liable to be drawn into the cylinders of the engine and it is, therefore, necessary to break the vacuum in the exhaust pipe, then this water enters the chamber 10 and if the water therein rises from $1\frac{1}{2}$ " to 2", for instance, the float 15 rises and stem 16 engaging the head 33 causes the upward movement of the stem 27 and pushes the spherical valve 22 from its seat on bushing 20. This permits steam from the pipe 19 to pass downward around the spherical valve and around the upper end of the stem 27 and into the chamber 26 and thence by pipe 26^a to the cylinder 33, causing the upward movement of the piston 34, which causes the lifting of the vacuum breaking valve 37, and this valve 37 remains raised until the level of the water in the receptacle to which the chamber 10 is connected lowers or returns to its normal level. This return of the water causes the downward movement of the stem 16 and this permits the stem 27 to lower, which in turn permits the valve 22 to lower onto the seat 20, thus cutting off the supply of steam. The downward movement of the tubular stem 37 opens the exhaust port or ports 29, whereupon the steam contained within the cylinder 25 is exhausted back through the pipe 26^a into the chamber 26, up around the upper end of the tubular stem and downward through this stem and outward through the port or ports 29 into the chamber 25, and from thence out through the exhaust pipe 30. The amount of lift of the float is adjusted by using different length thimbles 42 slipped over the rod 16 in the process of assembling these thimbles resting loosely upon the upper head of the float 15 and limiting the upward movement of the float.

So far I have described a construction which is similar to the construction illustrated and described in my prior application above referred to and which is practically

identical with the construction illustrated in an application for patent filed by me on the 14th day of April, 1921, Serial #461359. As before stated, the main object of the present invention is to provide means whereby upon the closing of the push button of an automatic engine stop the vacuum breaking valve may be immediately raised without regard to the position of the float 15, and to that end I have provided an electro-magnetically actuated means which moves upward against the head 31 upon the closing of a suitable circuit. The mechanism whereby this is accomplished is as follows: The upper face of the head 11 has a centrally disposed well or depression 43 concentric to the opening for the stem 16, and disposed within this depression and extending through the underface of the head 16 is a brass bushing 44 through which the rod 16 slides. Loosely surrounding the rod 16 is a brass, tubular sleeve designated 45, and mounted upon the lower end of this tubular member is an annular armature of soft steel or like metal, designated 46, which is formed to fit loosely over the bushing 44 and to slide up and down with the sleeve 45. This sleeve 45 at its upper end carries a head 47 which is made of suitable composition and which extends above the sleeve 45 and loosely surrounds the stem 16. The upper edge face of this head bears against the under face of the head 31 on the lower end of the stem 27. The upper face of the armature 46 is conoidal in form and loosely surrounding the sleeve 45 and the head 47 is the annular core 48 of a solenoid or magnet which coacts with the armature 46.

Surrounding this core 48 is a coil 49 formed of thoroughly taped and shellacked copper wire. In actual practice #18 gauge copper wire is used and about 480' of this copper wire is used for the coil. This coil is contained within a casing 50 which constitutes a loose shell protecting the coil. The core 48 extends above the upper end of this shell. The housing shell 50 is provided with a cap or top 51 which extends inward from the upper end of the shell and then upward, as at 52, and surrounds the upper end of the core 48. This core in turn loosely surrounds the head 47 which is carried upon the upper end of the sleeve 48. A plurality of set screws 53 extend through the upwardly extending portion 51 and engage the upper end of the core 48 so as to hold the core in place and under the screws 54 may be used to engage the set screws to hold them firmly and prevent chance of detachment.

The head 47 adjacent its lower end is formed with an annular channel 55 and a locking pin 56 is loosely mounted in and extends diagonally downward through the wall 52 and the upper end of the core and

bears against the outer surface of the head 47. When the head 47 rises under the magnetic action, this pin will drop into the annular recess 55 (see Figure 10) and having 5 dropped into this recess acts as a lock preventing the downward movement of the head 47, the sleeve 45, and the armature 46. The ends of the magnet coil are carried out 10 through the wall of the shell 50 and carried to binding screws 57 mounted upon the head 11 and insulated therefrom. From these binding screws conductors lead to a push button 58 and to a source of energy, so that when the push button is closed, the 15 magnet will be energized, drawing upward on the sleeve 45 and causing the operation of the valve in the manner heretofore stated.

The push button is illustrated as typifying any means whereby the circuit can be 20 closed through the magnet either automatically upon the happening of a predetermined event or by hand. Thus this push button may form part of an engine accident stop designed to be used when there is an 25 accident of any kind and it is desired to stop the engine. I do not wish to be limited 30 to the particular means employed for closing the circuit through the magnet or solenoid, as any suitable means may be used 35 for this purpose. Preferably the core 48 of the solenoid is formed of brass, and the outer shell 50 of wrought iron. It will be 40 obvious that when an electric current of sufficient voltage passes through the coil, 45 the lower pole or armature 46 will be raised up into contact with the upper or fixed pole formed by the lower end of the core and in so doing the striker head carried by the sleeve 45 will come in contact with the 50 head 31 of the steam valve rod and thereby raise the steam valve to a proper position to actuate the piston of the motor and raise the vacuum valve to destroy the 55 vacuum.

In the operation of this device, an observer touches the electric push button in 60 some part of the mill or other place where the mechanism is located, and if this push button is connected to the accident engine stop steam will be immediately shut off from the engine and at the same instant of time the solenoid will be energized to open the steam valve, as before described, to thereby destroy the vacuum even before the 65 machinery is still. When the striker head 47 has reached a certain height, the locking pin will drop by gravity into the recess 55 and the steam valve will be held open until an attendant withdraws the locking pin, 70 thus allowing the movable pole to return to its original position. It is to be noted, of course, that the solenoid or magnetic means for operating the steam valve is entirely distinct from, though it coacts with, 75 the float operated means for operating the

steam valve. Thus when the float rises and lifts the stem 27, it does not in any way affect the armature 46 because the rod 16 slides through the center of this armature and on the other hand when the armature is 80 raised by the energizing of the magnet or solenoid, this does not affect the rod 16 but the armature simply slides upon this rod as upon a guide. The upward movement of either the armature or the rod 16 acts 85 upon the head 31 to cause the lifting of the stem 27 and the lifting of the valve 22 from its seat.

It will be seen that in this construction 90 no steam or water packing is used, that all the movements are vertical, that the mechanism is extremely compact, that it has abundant power for the purpose described, and that the parts do not require frequent adjustment or repair. Further, it will be seen 95 that I have provided an automatic lock to hold the vacuum broken during all the time that the circuit is closed through the accident engine stop and that the action is instantaneous upon the closing of this circuit. It is also to be noted that by using the ball valve 22, I provide means whereby the valve may be free to rotate and seat at any point to which it may be rotated. By providing a plurality of exhaust 100 ports 29 extending radially from the tubular portion of the stem 27 and discharging these exhaust ports into an annular relatively large exhaust chamber 25, I permit the rotation of the stem 27 within the valve 105 casing 18 and prevent any chance of the stem at any time getting into such position that the exhaust port cannot be closed or opened.

While I have illustrated a construction 110 which has in actual practice been found thoroughly effective, yet it is obvious that many changes might be made in the details of construction and arrangement of parts without departing from the spirit of the invention.

One advantage of this electrical magnetically operated means for opening the vacuum breaker valve is that it causes the stoppage of the engine much more quickly than 115 would be the case where only the ordinary accident engine stop is used, and as a matter of fact insurance companies today require that there shall be an electric trip for the vacuum valve connected in line with 120 the accident engine stop. My construction provides practically a single means whereby the vacuum valve may be raised and the vacuum broken when the water rises in the condenser, as before explained, and means 125 whereby the vacuum valve may be raised and the vacuum broken whenever the accident engine stop is actuated, thus doing away with the use of two separate and independent devices and providing what is prac- 130

tically a single device for opening the vacuum valve under certain circumstances.

I claim:—

1. The combination with a vacuum breaking valve, of float controlled means for shifting the valve from its seat, and electro-magnetically controlled means for shifting the valve from its seat, the two means operating independently of each other.
2. The combination with a vacuum valve, of means for shifting said valve comprising a cylinder, a piston therein operatively connected to the valve, a float controlled valve in one position admitting motive fluid beneath the piston and in another position cutting off the flow of motive fluid to the space beneath the piston and permitting the discharge of motive fluid from said space, and electro-magnetic means for shifting said controlling valve to a position to admit motive fluid beneath the piston and including means for closing a circuit through the electro-magnetic means.
3. The combination with a controlling valve having a longitudinally shiftable valve stem, of an armature, a stem connected thereto and disposed in alignment with but normally spaced from the valve stem and adapted to contact therewith when the armature is shifted, and an electro-magnet connected in an interrupted circuit with a source of energy, the electro-magnet coacting with the armature.
4. The combination with a valve having a valve stem, of a float having a stem adapted to engage with the valve stem to cause the shifting of the valve stem into one position when the float is raised, electro-magnetic means for shifting said valve stem including a sleeve loosely surrounding the float stem, said sleeve when raised engaging the valve stem, an armature connected to the sleeve, and an electro-magnet adapted to be connected with a source of energy and when energized attracting the armature and causing the shifting of the sleeve and the actuating of the valve.
5. The combination with a controlling valve having a stem, the lower end of the stem being provided with a head, of a float, a stem adapted when the float rises to engage said head to shift the valve stem, a sleeve loosely surrounding the float stem

and independently shiftable with relation thereto and adapted when raised to engage 55 said head to raise the valve stem, an armature carried by said sleeve, and an electro-magnet surrounding the sleeve and coacting with the armature, said magnet when energized attracting the armature and causing 60 the sleeve to strike the valve stem to thereby shift the valve.

6. The combination with a float chamber having a float therein and a controlling valve mounted above the float chamber and including a longitudinally shiftable valve stem and having a head at its lower end, of a stem mounted upon the float extending upward in alignment with the valve stem but out of contact therewith and adapted 70 when the float rises to strike the head of the valve stem and shift the valve, a sleeve surrounding the float stem and having a head at its upper end adapted when the sleeve is lifted to strike the head on 75 the lower end of the valve stem to lift it, an armature attached to the lower end of the sleeve, and an electro-magnet surrounding the sleeve and adapted when energized to attract the armature to thereby lift it. 80

7. The combination with a vacuum breaking valve, of fluid actuated means for causing the lifting of the valve, electrically actuated means for lifting the valve independently of the fluid actuated means, and 85 means for locking the valve in its raised position, said means being manually releasable from its locking position.

8. The combination with a vacuum valve, of fluid actuated means for raising the 90 vacuum valve from its seat and including a controlling valve, float operated means for shifting the controlling valve to cause the lifting of the vacuum valve, electrically operated means for shifting the controlling 95 valve to thereby cause the lifting of the vacuum valve, and automatically acting means locking the controlling valve in its shifted position after it has been actuated by the electrically actuated means, said 100 automatically acting means being manually releasable from its locking position.

In testimony whereof I hereunto affix my signature.

WALDO A. HOWLAND.
